United States Patent [19]

Nagel

[11] Des. 264,356

[45]  May 11, 1982

[54] ELECTRONIC GAME HOUSING

[75] Inventor: Dietmar Nagel, Chester, N.J.

[73] Assignee: Nagel-Kennedy & Associates, New York, N.Y.

[] Term: 14 Years

[21] Appl. No.: 120,561

[22] Filed: Feb. 11, 1980

[51] Int. Cl. .... D21—01

[52] U.S. Cl. D21/13

[58] Field of Search ..... D21/13; 273/1 E, 85 G,
273/138 A

[56] References Cited

PUBLICATIONS

Spiegel Xmas Cat., 1978, p. 368, item D, Blip.

The Washington Post, Jul. 28, 1977, p. D20, Radio Shack Advt., Electronic Video Fun Game.

Playthings, Apr. 1979, p. 28, top, Electronic Sea Battle.

Primary Examiner—Melvin B. Feifer

[57] CLAIM

The ornamental design for an electronic game housing, substantially as shown and described.

DESCRIPTION

FIG. 1 is a perspective view from the right side of an electronic game housing showing my new design;

FIG. 2 is a top plan view thereof;

FIG. 3 is an inverted elevation view from one end thereof;

FIG. 4 is an elevation view from the other end thereof; and

FIG. 5 is a left side elevation view thereof.

FIG. 1

FIG. 2

FIG. 3

FIG. 5

FIG. 4